RICHARD C. COUPLAND, OF THE UNITED STATES ARMY, OF NORFOLK, VIRGINIA

COOLING JACKET FOR MACHINE GUN BARRELS

Application filed January 9, 1931. Serial No. 507,613.

(GRANTED UNDER THE ACT OF MARCH 3, 1883, AS AMENDED APRIL 30, 1928; 370 O. G. 757)

The invention described herein may be manufactured and used by or for the Government for governmental purposes, without the payment to me of any royalty thereon.

The subject of this invention is a cooling jacket for machine gun barrels.

The general practice in cooling machine gun barrels consists in surrounding the barrel with a liquid and inasmuch as the barrel has a reciprocatory movement it is necessary to provide a packed joint to prevent leakage.

In the present invention it is proposed to provide the cooling jacket in the form of an annular casing, the liquid in the jacket being out of contact with the gun barrel. By virtue of this arrangement the packed joints are eliminated and the jacket may be readily attached to and detached from the gun without disturbing the barrel.

The invention is further characterized by a novel method of venting the jacket when the vapor pressure reaches a predetermined value.

With the foregoing and other objects in view, the invention resides in the novel arrangement and combination of parts and in the details of construction hereinafter described and claimed, it being understood that changes in the precise embodiment of the invention herein disclosed may be made within the scope of what is claimed without departing from the spirit of the invention.

A practical embodiment of the invention is illustrated in the accompanying drawing, wherein:

Fig. 1 is a view in side elevation of a machine gun equipped with the improved cooling jacket;

Fig. 2 is a plan view thereof;

Fig. 3 is a longitudinal sectional view of the cooling jacket;

Figs. 4 and 5 are detail sectional views on the respective lines of Fig. 2.

Referring to the drawing by numerals of reference:

There is shown a machine gun comprising a receiver 5 and a barrel 6 supported in bearings 7-7 of the receiver and attached to a reciprocally mounted member 8.

The cooling jacket 9 surrounding the barrel consists of an annular casing formed of an outer corrugated tube 10 and an inner tube 11 maintained in spaced relation by a front end cap 12 and a rear end cap 13. The rear cap 13 is formed with spaced concentric annular extensions 14 and 15 fitting respectively on the inside and the outside of an annular lip 16 of the receiver. The jacket is securely attached to the receiver by means of a threaded connection 17 which in the present instance is associated with the inside extension 14.

Secured to the outer tube 10 adjacent its extremities are a pair of blocks, the rear block 18 being wholly within the tube and the forward block 19 partially protruding therefrom. An inlet passage 20 in the forward block 19 leads to a valve passage 21 which in turn is in communication with an outlet passage 22. A ball valve 23 movable in opening 70 towards the outlet passage is normally held closed by a spring 24 seated on a plug 25. A tube 26 mounted in the blocks 18 and 19 is open to the valve passage 21 in the forward block and to an inlet passage 27 in the rear block. This arrangement permits the vapor of the liquid to be exhausted from the jacket irrespective of the inclination of the jacket.

Bell crank levers 28 and 29 respectively mounted in the rear and the forward blocks 18 and 19 each carries a ball valve, 28a and 29a, arranged to close the inlet passages in the blocks. A rod 30 connects the levers 28 and 29 and serves as a gravity actuator to simultaneously operate the levers.

When the jacket is in horizontal position the valves 28a and 29a will both be in the open position (Figs. 4 and 5) above the level of the cooling liquid but when the jacket is inclined the lowermost valve will be closed.

to prevent the liquid from entering the passages leading to the outlet passage 22. The vapors generated when the liquid becomes heated will be vented when the pressure exceeds the load on the ball valve 23.

5 The outer tube 10 is provided with an opening 31 for introducing the cooling liquid into the jacket and also with an opening 32 for draining the jacket.

10 By virtue of the complete independence of the cooling jacket with respect to the barrel, either one of these members may be removed without disturbing the other and without the necessity of draining the liquid from the jacket.

15 The arrangement is particularly adapted for the employment of an agent having a high boiling point such as ethylene-glycol or di-ethylene-glycol. The purpose in view is to permit a high rate of firing and to increase the number of rounds fired before the agent in the cooling jacket reaches a temperature of vaporization. The high differential between the temperature of the jacket and the temperature of the atmosphere induces a considerable drop in temperature of the agent immediately upon cessation of firing through the barrel.

I claim:

30 1. A cooling jacket for guns, comprising an inner tube adapted to fit over a gun barrel, a corrugated outer tube, annular end caps connecting the tubes in spaced relation, and gun-attaching means on one end cap.

35 2. A cooling jacket for guns, comprising an inner tube adapted to fit over a gun barrel, an outer tube, annular end caps connecting the tubes in spaced relation, and gun-attaching means on one end cap.

40 3. A cooling jacket for guns comprising an enclosed annular casing adapted to fit over a gun barrel and gun-attaching means on one end of the casing.

45 4. In combination with a gun barrel, an enclosed annular casing surrounding the barrel and independent thereof, and means for introducing a liquid into the casing.

50 5. In a cooling jacket for guns, a casing, a block on the inside wall of the casing adjacent each end, an inlet passage in each block, a valved outlet in one of the blocks, a tube connecting the blocks and establishing communication between the inlet passage in one block and the valved outlet in the other block, a bell crank lever carried by each block and arranged to close the inlet passage of said block, and a rod connecting the levers.

55 6. In a cooling jacket for guns, a casing, a block on the inside wall of the casing adjacent each end, an inlet passage in each block, an outlet in one of the blocks, a tube connecting the blocks and establishing communication between the inlet passage in one block and the valved outlet in the other block, a pivotal-

ly mounted valve for closing each inlet passage and a rod connecting the valves.

7. A cooling jacket for guns embodying an enclosed casing providing an annular chamber and adapted to fit over a gun barrel, and gun attaching means at one end of the casing.

8. A cooling jacket for guns embodying an enclosed casing providing an annular chamber and adapted to fit over a gun barrel and means for introducing a cooling fluid into the casing.

9. In combination with a gun barrel, a fluid container fitting over the barrel and being out of fluid communication with said barrel.

10. In combination with a gun barrel, a cooling jacket including an inner tube fitting around the barrel and slideable relative thereto.
